UNITED STATES PATENT OFFICE

JAMES B. KIRBY, OF WEST RICHFIELD, OHIO

CENTRIFUGAL MACHINE

Application filed June 7, 1926. Serial No. 114,191.

This invention relates chiefly to centrifugal machines and has for its object the provision of a new and improved driving mechanism therefor which shall facilitate their operation and permit the use of smaller and cheaper motors than heretofore employed; the provision of new and improved expedients for applying the full power of the motor for purposes of accelerating the motion without slipping of belts or other friction devices and without danger of overloading the motor; the provision of new and improved means for supporting, centering, idling, and braking the device; the provision of new and improved safety devices therefor, while further objects and advantages of the invention will become apparent as the description proceeds.

I have illustrated my improvements in connection with a laundry apparatus by which clothing and fabrics are centrifuged but it will be understood that the same or much similar devices can also be employed for driving cream separators, vehicles, etc., wherein the load and speed are variable and wherein the maximum power available is definitely limited.

In the drawings I have chosen for illustrative purposes a simple, self-contained, domestic-laundry, centrifuge, although it will be understood that these drawings are intended to be merely illustrative of the principles of my invention and not limiting upon me as regards either construction or uses.

Fig. 1 is an end elevation of a domestic-laundry centrifuge containing my improvements; Fig. 2 is a vertical sectional view corresponding to the line 2—2 of Fig. 1; Fig. 3 is a horizontal sectional view corresponding to the line 3—3 of Fig. 2; Fig. 4 shows a modified form of stop and brake mechanism; Fig. 5 is a top plan view of a modified form of driving mechanism; and Fig. 6 is an end elevation of the device shown in Fig. 5.

The centrifuge illustrated in Figs. 1 and 2 comprises essentially a foraminous basket or container 1 concentric about a vertical axis and mounted on a vertical shaft 2, the whole being housed inside an upright metal casing 3, supported by legs 4—4. In the present embodiment this casing 3 is a self-contained

device but it is within my invention to form it as a part of any other convenient unit such as a washing tub. I have shown the casing as provided with a rigid top 5 having a central opening 6 registering with a similar opening in the basket 1 and provided with a cover 7 hinged at 8 and formed with an upturned flange 9 along the end wall of the casing. The bottom of the casing is formed with a vertical central curb 10 of sufficient diameter to accommodate the shaft 2 and its attached parts and also spaced sufficiently from the side walls of the casing to define an annular chamber or well 11 for the reception of the extracted liquid, the bottom of this well being provided with a suitable outlet 12. The bottom of said container is formed outwardly of the wall 10 with a depending drip rib 13 here defined by the junction between the outer wall of the container and the outwardly and downwardly slanted bottom wall 14 thereof so as to insure the delivery of all the drip to the chamber 11 and prevent it from running down the shaft or falling through the space inside this wall.

According to a preferred form of the device the shaft 2 is normal to and rotatable with the horizontal circular friction plate 15 by which the container or basket is both supported and driven. In the present embodiment the legs 4—4 are connected in pairs by horizontal members 16—16 which in turn are connected by the horizontal girder 17 provided at the center with a vertical elongated bearing sleeve 18 in which is mounted the vertical shaft 19 whose upstanding end receives the hub 20 of the plate 15. The lower end of the shaft 2 terminates in a spider 21 whose arms merge in the ring 22 which is secured to this friction plate through the medium of an annular cushioning member 23 of soft rubber or material having the herein essential properties of soft rubber.

Carried by the girder 17 and by a second girder 25 spaced therefrom are bearings 26, 27 in which is journaled a horizontal shaft 28 on which is mounted a friction disk 30. This disk is not rigidly attached to its shaft but is loosely threaded thereon as indicated at 31, and is yieldingly held adjacent to one

end of such thread by means of a spring 32.

In the present embodiment the wheel 33 also serves for the transmission of power to the shaft 28, being connected by a belt 35 to

5 the drive pulley 36 of a motor 37 carried by one of the members 16. The direction of driving is very important since it must be such as to tend always to screw the shaft 28

10 into the disk 30 and thereby draw this disk 15 outwardly towards the periphery of the plate 15. The machine is so designed that with the motor 37 operating at its full normal speed

15 and the disk 30 at its innermost position as shown in Figs. 2 and 3, the basket 1 will be rotated at its maximum desired velocity.

Upon starting the device, however, especially with a heavy load in the container 1, the inertia of the latter causes the motor to overrun, thereby screwing the shaft 28 into the

20 disk 30 and thereby drawing the disk towards the periphery of the plate 15 thus changing the speed ratio and affording the motor an increased mechanical advantage.

25 The degree of change of ratio depends upon the stiffness of the spring 32, and this depends upon the size and construction of the motor and length of time which the acceleration is designed to cover. In the case of a

30 carefully made machine or one mounted on ball bearings and running very easily when once started (such as a cream separator) it is possible to employ a very small motor by using a comparatively light spring 32 and permitting a very large decrease in speed

35 ratio, but with the result of requiring a correspondingly long period for acceleration; on the other hand by using a more powerful motor and a stronger spring, the speed ratio is less changed and the acceleration period is

40 shortened. As the container velocity increases and its opposition decreases, the spring 32 gradually restores the disk 30 to its initial position as shown in Figs. 2 and 3 with the result that both the motor and

45 container are soon running to their respective speeds of highest efficiency.

In order to control the operation of the container I have shown in Figs. 1, 2, and 3 a hand lever 40 pivoted to a horizontal boss

50 41 carried by the girder 17 and provided with a radial arm 42 to which is journaled a horizontal idler wheel 43. This idler is mounted with its axis radial to the shaft 19 and in a position to receive and support the disk 15.

55 The extremity of the arm 42 is provided with a brake shoe 45 adapted to engage the disk 15. The upper end of the lever 40 projects above the top of the casing and above the edge of the flange 9, its motion being guided

60 by a rod 46, carried by the end of the casing, the latter being preferably formed with lugs 47 cooperating with a dog 48 operatively connected in the usual manner with a detent handle 50. When the lever stands in the position shown in Fig. 1 the brake shoe 45

presses against the plate 15 and actually lifts the same away from the disk 30. The end of the lever is also out of range with the flange 9 permitting the cover 7 to be readily lifted. As the lever 40 is moved to the center position the shoe 45 moves more rapidly than the idler 43, thereby lowering the plate into contact with the latter which in turn holds it out of engagement with the disk 30. The container can now turn freely. As the lever is moved still further to the right the plate 15 is lowered onto the disk 30 which when rotated starts it into operation as heretofore described, the lever now preventing opening of the cover. It is possible either by moving the lever to the half way position to allow the tub to spin freely a long time and come to rest gradually, or by drawing the lever more forcibly to the left to put on the brake with any desired degree of vigor. The elevation of the plate from the disk 30 is advantageous in preserving the disk, which is generally provided with a tire of softer material, from becoming deformed or flattened while the machine is standing. It will be understood that the motor 37 can be used for other purposes also or may be shared with other machinery.

In Figs. 4 and 5 I have illustrated a modified arrangement of brake. The same lever 40 is employed and has an arm 42 carrying a roller 43 by which the plate 15 is lifted off the disk 30, but the brake shoe 45^a instead of being carried by this arm is mounted on a part of the casing 1 or its frame above the plate, the latter being elevated into contact with it by the action of the lever 40. In this case it is not always convenient to maintain the brake shoe at such a point as to guarantee the application of the brake at the time the cover is opened as in Fig. 1 although the container is at least lifted off the power element, and in neither case can the power be applied until the cover is closed.

In Figs. 5 and 6 I have illustrated a modification of my invention, the parts being mostly reversed in position, but operating under the same essential theory. In this case the friction plate 60 is the driving member instead of the driven member and is connected directly to the armature shaft of the motor 61 instead of being belted thereto. A shaft 62, now the driven member instead of the driving member, is mounted in bearings 63-63 so as to traverse the face of the plate 60 and on which is loosely screwed the friction disk 64 whose face is, as usual, provided with a soft tire 65. Power is taken off the shaft 62 in any suitable manner as by the pulley 66. Screwing of the disk 64 along the shaft is opposed by the spring 67 interposed between said disk and an abutment member 68. Upon starting the motor 61, assuming the load on the shaft 62 to be heavy, the disk 64 will be screwed along the shaft to a point

nearer the center of the plate 60 where the mechanical advantage is sufficiently increased to enable the motor 61 to move the same, but as the speed of the shaft 62 increases and its opposition becomes less, the spring 67 gradually returns the disk towards the periphery of the plate until both the driving and the driven member reach their full speed. It will be seen that when the plate is the driving member it is necessary for the disk to move inwardly in order to secure the desired change of speed ratio, but where the plate is the driven member it is necessary for the disk to move outwardly to obtain this result. In each case the mechanical advantage is temporarily increased against the tension of the spring by an amount necessary to reduce the load on the motor to the desired degree. This mechanism adapts itself, not only to the condition of starting a machine into operation, but also of delivering a predetermined power input into a machine of variable speed. If while the machine is running the load on the driven member be varied in any way, the friction disk immediately moves inwardly or outwardly as the case may be to accommodate the change, the power input remaining substantially the same up to the full capacity of the driving element but on the other hand preventing overloading of that element under any conditions.

It will be understood that I have shown herein both a mechanical movement of general utility and a specific machine, namely, a laundry centrifuge, containing such element. Some features of the mechanical movement are useful with other devices than laundry machines, and some features of the centrifuge are valuable with other driving devices, and some features of each produce their fullest effect only in combination with the other, so that I do not limit myself except as specifically recited in my several claims.

Having thus described my invention what I claim is:

1. In a centrifugal machine, in combination, a vertical shaft, a horizontal friction plate carried thereby, a pad of material having the herein essential properties of soft rubber carried by said plate, a spider mounted

50 on said pad, an upright shaft carried by said spider, a container carried by said shaft, and a friction disk supporting and driving said plate.

55 2. In a centrifugal machine, in combination, a vertical shaft, a horizontal friction plate carried thereby, a pad of material having the herein essential properties of soft rubber carried by said plate, a spider mounted 60 on said pad, an upright shaft carried by said spider, a container carried by said shaft, a friction disk adapted to support and drive said plate, and a lever having a part adapted to engage said plate and elevate it out of contact with said disk.

3. In a device of the character described, in combination a frame comprising legs and a horizontal member, a vertical bearing carried by said member, a vertical shaft in said bearing, a horizontal circular plate carried by said shaft, a second vertical shaft carried by said plate, there being a yielding substance between said plate and second shaft, a horizontal shaft journaled to said frame below said plate, a friction disk carried by said last shaft and engaging said plate, and means for driving said last shaft. 70 75

4. In a centrifuge, in combination, a horizontal shaft, a disk thereon, a vertically movable horizontal circular plate resting on said disk, a vertical slideable bearing for said plate, a vertical shaft centrally carried by said plate, there being a yielding connection between said plate and vertical shaft, and a rotatable container carried by said vertical shaft. 80 85

5. In driving mechanism the combination with a driving member and a driven member, one of which has a friction plate and the other a friction disk whose edge bears against the face of said plate, of a shaft on which said disk is threaded, said plate and disk constituting the power transmitting means between said driving member and said driven member, and a spring yieldingly forcing said disk toward that end of the thread where the mechanical advantage from the driving to the driven member is least. 90 95

6. The combination with a friction plate of a rotatable shaft parallel to and spaced from the face thereof and having screw threads thereon, a friction disk screwed on said shaft, a driving and a driven member, one attached to said plate and the other to said disk, said plate and disk constituting the power transmitting means between said driving member and said driven member, the direction of twist of said thread being such that the transmission of power tends to screw said disk along its shaft to a position to increase the mechanical advantage, and spring means operatively connecting said disk and shaft and tending to move the disk in the opposite direction. 100 105 110

7. The combination with a driving member and a driven member, one of which has a friction element and the other of which has a friction disk presented edgewise thereto, of a shaft for said disk parallel to an element of said surface, said shaft and disk being loosely screwthreaded together, and a spring operatively connecting said disk and shaft and tending to screw the disk in a direction to decrease the mechanical advantage of the drive, said plate and disk constituting the power transmitting means between said driving member and said driven member. 115 120 125

8. The combination with two shafts set at right angles to each other, one of the same being threaded, of a friction disk loosely 120

screwed on the threaded shaft, a cooperating friction plate carried by the other shaft, a spring secured to said threaded shaft and tending to keep said disk at the high speed 5 end of its thread, and power connections to and from said shafts, said disk and plate constituting the sole power transmitting connection between said shafts.

9. In a centrifugal machine, in combination, a vertical shaft, a horizontal friction plate carried thereby, a friction disk adapted to support and drive said plate, a vertical shaft having an elastic gyration-permitting connection to said plate, and a centrifuge container rigidly secured to said shaft.

In testimony whereof I hereunto affix my signature.

JAMES B. KIRBY.
